UNITED STATES PATENT OFFICE.

JAMES McMILLAN AND WILLIAM AFFLECK ROBERTSON, OF GLASGOW,
COUNTY OF LANARK, SCOTLAND.

APPARATUS FOR FEEDING FUEL TO FURNACES.

SPECIFICATION forming part of Letters Patent No. 289,354, dated November 27, 1893.

Application filed April 16, 1893. (No model.)

To all whom it may concern:

Be it known that we, JAMES McMILLAN and WILLIAM AFFLECK ROBERTSON, both of Glasgow, in the county of Lanark, Scotland, have 5 invented new or Improved Apparatus for Feeding Fuel to Furnaces, (for which we are about to apply for Letters Patent in the Empire of Germany,) of which the following is a specification.

10 Our said invention relates to new or improved apparatus for the feeding of fuel to furnaces and fire-places, and has for its object the prevention of smoke by the feeding of green fuel up through the bottom of such furnaces 15 or fire-places and underneath the live fuel.

In the case of apparatus constructed according to our invention for feeding fuel into the furnace or fire-grate of a steam-boiler or other analogous furnace or fire-grate, it consists of 20 a fuel-box, preferably of rectangular form, mounted on flanged rollers, which traverse upon horizontal rails or guides parallel with the plane of the furnace-bottom. In the furnace bottom or grate an opening is formed of about 25 the same shape and dimensions as the shape and dimensions taken horizontally of the interior of the box hereinbefore mentioned. A "dead-plate" is also provided of rather larger dimensions than the opening in the furnace-bottom, 30 and which, like the box hereinbefore mentioned, is mounted on flanged rollers, which also traverse horizontally upon the rails or guides. The dead-plate may either be rigidly connected to the box or it may be provided 35 with an automatic coupling device for engaging and disengaging with the same at the required part of the travel of the fuel-box, in which case the dead-plate is provided with a projection, which, when the fuel-box carrying 40 the green fuel to be charged into the furnace or fire-grate is pushed inward, engages with a hook at the inner end of the fuel-box, and, as the inward motion of the fuel-box is continued, pushes away the dead-plate from beneath the 45 opening in the furnace-bottom. In proportion as the box containing the fuel advances underneath the said opening the dead-plate is pushed into its farthest rearward position.

The fuel-box has a movable bottom in it, which 50 is capable of being moved upward and downward, and when it is beneath the opening in the furnace-bottom the movable bottom of the

box is moved upward, thereby forcing the green fuel into the furnace beneath the live fuel. So soon as this is effected the fuel-box 55 may be withdrawn, and the dead-plate, being still coupled to it by the hook hereinbefore mentioned, is drawn backward with the box until the dead-plate closes the said opening, at which position the hook which couples it to 60 the fuel-box is disengaged from the projection upon the dead-plate, so that the dead-plate is left beneath the opening, and the fuel-box is carried backward into its position for charging, where the bottom of the same is lowered, in 65 order that the box may receive its next charge. The bottom of the fuel-box may be raised either by crossed levers or by jointed arms, both of which methods are operated by a right-and-left-handed screw acting upon nuts jointed to 70 the lower ends of the said levers or arms; or the said levers may be operated by means of eccentrics carried upon a horizontal shaft, which, being rotated through half a revolution, raises or lowers the bottom of the fuel-box. 75

For the operation of the different motions required from the charging of the fuel-box to the return of the same empty into the position for recharging, there is provided a horizontal screw, carried at the rearward end in a bearing, and operated at its forward end by a motor or by gearing for hand-driving. This screw is provided at its forward and rearward ends with clutches, which engage at the required time with the right-and-left-handed 85 screw hereinbefore mentioned, simultaneously with which motion pawls engaging with the nut through which the horizontal screw works are disengaged by means of cam devices formed on the horizontal rails, the effect of these motions being to retain the fuel-box in the same horizontal position while the bottom of the 90 same is being raised or lowered.

In the drawings, Figure 1 is a longitudinal section of mechanism constructed according to 95 and constituting the first part of our said invention. Fig. 2 is a front elevation of the same. Figs. 3 and 4 are transverse sections of the same. Fig. 5 is a longitudinal section of a modified form of mechanism constructed 100 according to and constituting the first part of our said invention. Fig. 6 is a part section and part front elevation of the same. Fig. 7 is a front elevation of a detached portion of

the same. Fig. 8 is a longitudinal section of a further modification of our said invention.

When a backward motion is imparted to the fuel-box *a* in order to bring it beneath the opening *b*, to discharge the contents of the same into the furnace, the handle *c* is turned in the direction of the arrow *d*, which causes a reverse motion to be transmitted to the screw *e* through the gear-wheels *f* and *g*. When the fuel-box *a* has arrived beneath the opening *b* the contents thereof are caused to be raised through the same by the rotation of the right-and-left-handed screw *h*, which, through the levers *i*, or (as represented at Fig. 8) arms *j* and *k*, raises the movable bottom *l*, and with it the charge carried upon it. This action of the screw *e* is effected by means of the weighted pawl *m* being disengaged from the ratchet-teeth *n*, which are formed upon the forward end of the right-and-left-handed screw *h*. This pawl *m* is disengaged by means of its lower end, which carries the anti-friction roller *o*, being depressed on coming into contact with a cam formed upon the under side of the rail or guide *p*. Simultaneously with this action the clutch *q*, formed on the rearward end of the right-and-left-handed screw *h*, engages with the clutch *r*, fixed upon the screw *e*. When the contents of the fuel-box *a* have been charged into the furnace the motion of the handle *c* is reversed—that is to say, it is turned in the direction represented by the arrow *s*—by which means the screw is similarly turned in a reverse direction, and the clutches *q* and *r* are forced apart, and the pawl *t*, engaging with the ratchet *n* in a reverse direction to that in which the pawl *m* did during its rearward travel, the box *a* is caused to travel in a forward direction until the pawl *t* is disengaged from the ratchet *n*, in a similar manner to that hereinbefore described for disengaging the pawl *m*. Simultaneously with this motion the clutch *u* upon the forward end of the right-and-left-handed screw *h* engages with the clutch *v*, fixed upon the screw *e*, and the movable bottom *l* is thereby lowered by the same means as those described for raising it.

At the rear end of the fuel-box *a* the hook *w* is pivoted, which is connected to a short shaft running sidewise. At the other end of this shaft a hinged arm, *x*, is attached in such a manner that by its means the hook *w* can only be raised when the fuel-box *a* is being moved in a forward direction, when the arm *x* comes into contact with the projection *y*, formed on the rail or guide *p*, while in traveling in a rearward direction the hook *w* is allowed to engage with the coupling-loop *z* on the dead-plate *a'*, which travels with the fuel-box *a* until disengaged from it by the lifting of the hook *w* when it is traveling in the forward direction.

The dotted lines *b'* represent a rigid connection between the dead-plate *a'* and the fuel-box *a*. This form of construction, which takes the shape of a prolonged dead-plate, may be

adopted in cases where sufficient room can be spared for the rearward travel of the dead-plate. It is found to be of special utility when applied to vertical boilers.

When the mechanism hereinbefore described is driven by a motor through gearing, as represented at Figs. 5 and 6, there is fitted upon the forward end of the screw *e* a bevel-wheel, *c'*, gearing with which are the two bevel-wheels *d'* and *e'*, which are carried loosely upon the shaft *f'*. Upon the inner faces of the bevel-wheels *d'* and *e'* the clutches *g'* and *h'* are formed, and between these the striking-clutch *i'* is fitted upon a "feather," so that it may be engaged with either of the clutches *g'* and *h'*, according to the direction in which the fuel-box *a* is required to travel. To automatically reverse the mechanism, when the contents of the fuel-box *a* have been charged into the furnace, there is provided the shaft *j'*, which is driven from the shaft *f'* by the gear-wheels *k'* and *l'*. Upon the shaft *j'* is mounted the screw *m'*, which gears with the worm-wheel *n'*, to the face of which are fitted the adjustable screws *o'*. This mechanism is so adjusted that the clutch *i'* is thrown into its position necessary for the return of the fuel-box to its normal position by the adjustable screws *o'* at the time when the fuel-box *a* has discharged its contents up into the furnace, and thrown into its neutral position when it has arrived at the position necessary for receiving a fresh charge of fuel. Fig. 7 of the accompanying drawings represents a hood, *p'*, for inclosing the mechanism last described.

With reference to the apparatus hereinbefore described, it is to be understood that both forms thereof may be applied to furnaces or fire-places of both larger and smaller dimensions than the classes of such furnaces in connection with which they are herein particularly described.

We claim—

1. The fuel-box *a* and dead-plate *a'*, in combination with the pivoted hook *w* and its attached arm *x*, carried by the box *a*, the coupling-loop *z*, carried by the dead-plate *a'*, and the projection or cam *y*, substantially as hereinbefore set forth.

2. The right-and-left-handed screw *h*, for actuating the raising and lowering mechanism for the discharge of the fuel, in combination with the screw-propelling shaft *e*, the clutches *q* and *u*, and ratchet *n*, and pawls *m* and *t*, substantially as and for the purposes hereinbefore described, with reference to the accompanying drawings.

In testimony whereof we have signed our names to this specification in the presence of two subscribing witnesses.

JAMES MCMILLAN,
WILLIAM AFFLECK ROBERTSON.
